(57) CLAIM

The ornamental design for a racing high chair, as shown and described.

DESCRIPTION

FIG. 1 is a perspective view of a racing high chair according to my design;

FIG. 2 is a front view thereof;

FIG. 3 is a side view thereof; and,

FIG. 4 is a top view thereof.

The surfaces or portions of the article not shown in the drawing or described in the specification form no part of the claimed design.
